United States Patent Office

Des. 181,040
Patented Sept. 24, 1957

181,040

MARINE COMPASS

Leslie F. Carter, Leonia, N. J., assignor to Sperry Rand
Corporation, a corporation of Delaware

Application July 12, 1956, Serial No. 42,230

Term of patent 14 years

(Cl. D52—1)

FIG. 1.

FIG. 2.

Des. 181,040

PAGE 2

FIG. 3.

FIG. 4.

Fig. 5.

Fig. 1 is a perspective view of a marine compass showing my new design;
Fig. 2 is a side elevational view thereof;
Fig. 3 is a front elevational view thereof;
Fig. 4 is a top plan view thereof; and
Fig. 5 is a rear elevational view thereof.

I claim:
The ornamental design for a marine compass, as shown.
